UNITED STATES PATENT OFFICE.

OLIVER J. MARSHICK AND EDWIN L. CROSBY, OF DETROIT, MICHIGAN.

POURING MECHANISM FOR REFRACATORY FURNACES.

Application filed August 23, 1920. Serial No. 405,222.

To all whom it may concern:

Be it known that we, OLIVER J. MARSHICK and EDWIN L. CROSBY, citizens of the United States, residing at Detroit, county of Wayne, 5 State of Michigan, have invented a certain new and useful Improvement in Pouring Mechanism for Refractory Furnaces, and declare the following to be a full, clear, and exact description of the same, such as will 10 enable others skilled in the art to which it pertains to make and use the same, reference being had to the accompanying drawings, which form a part of this specification.

This invention relates to mechanism for 15 handling and elevating the drum of a rotatable or rockable refractory furnace, and has for its object an improved organization of parts, by means of which, when the metal under treatment has been sufficiently heated, 20 the drum may be easily tilted to a degree not heretofore attainable because of the necessary presence of other operative elements within its base line, in a way to make possible the practically continuous pouring 25 into molds located at the same distance from the furnace drum, since with our improved apparatus the pouring orifice is at all times in the same position relatively to the point where the molds are placed, with the drum 30 as a whole moved about it.

In the drawings:

Figure 1 is an end elevation of our improved apparatus.

Figure 2 is a side elevational view, showing 35 the relation of the pouring spout to the bar removably attached at one side of the drum when pouring is to begin.

Figure 3 is a side elevational view of the drum end of one of the hoisting members.

40 Figure 4 is an end elevation of a modified form of apparatus, in which the lifting of one side of the drum is done from above rather than from beneath, as by means of the jack shown in Figure 1.

45 A represents the rockable refractory lined drum, provided with a filling door B and a pouring spout hole C. Arranged about the periphery of the drum within each edge thereof are encircling metal bands composed 50 of the trackway portion E and tooth portion F, adapted to rest upon the supporting rollers D and D' and to be rotatably actuated by the gear G. Ordinarily the furnace drum is not rocked back and forth so that the pouring spout is much below the position shown 55 in Figure 1, although it may be moved to a

position directly beneath the central axis of the drum, as for emptying and cleaning out of the melting chamber. With a furnace constructed to oscillate thus, there is a relatively small space, within the line of the furnace drum, in which a mold can be rested when the metal is ready for pouring, since such space as there is is largely occupied by the supporting rollers and other operative 60 elements. Furthermore, after each mold is filled and further pouring from the spout C is halted by slight rocking of the drum in the reverse direction (to the right as shown in Figure 1), in order to permit the removal 65 of the filled mold and the substitution of another therefor, the quantity of fluid metal within the drum being thus diminished, for pouring into subsequently placed molds, the furnace drum would have to be rocked further around to a position where the pouring 70 spout is lower than before and consequently further than ever within the line of the drum.

To obviate this difficulty, we place on each 75 end of the furnace drum, in approximately the same peripheral position as the pouring spout C, a bracket or projecting arm O, through the perforated ends of which a bar J is thrust when the drum has been nearly 80 rotated to pouring position. A slight further downward turning movement of the drum then suffices to make this bar rest in the recessed top portions of the supporting 85 frames K which are located near the ends 90 of the furnace drum.

From a position peripherally distant from the pouring spout from one-third to one-half of the periphery of the drum, and located intermediate the encircling metal 95 trackways near each edge, is a projecting strut L, from which laterally extends a trunnion stud M which is adapted to rest in the troughed or recessed upper end N of the hoisting jack P, which engages in the complementarily threaded block Q, the teeth 100 of whose gear are adapted to be engaged by those of a complementary gear S mounted on the shaft of the actuating motor T.

With the bar J resting firmly in the top 105 of the frame K, the lifting of the jack P begins under actuation from the motor T, thus serving to lift the entire drum A from its position upon the right hand pair of supporting rollers D' (as shown in Figure 1) 110 and elevating it to the dotted line position shown in Figure 1. The path of the trun-

nion M, on the right hand side of the drum, not being a truly vertical one, but rather following the arc of a circle whose center is the bar J, provision is made whereby the 5 trunnion U enables the jack P to follow the slightly curved course indicated by the dotted line (b) without displacement of its connected parts.

With the drum A in the dotted line position shown, the horizontal top level of the 10 molten metal within the drum A is now lowered to the level of the dotted line (a). The pouring spout is thus left in a position sufficiently far out from the supporting rollers beneath the drum A, so that a continuous 15 succession of molds may be moved into receiving position, relatively thereto, as by means of a turnable table about whose outer edge the empty molds are spacedly arranged, 20 or by means of an endless belt or traveling platform I, running along the floor just beneath the pouring position of the spout C. After pouring, the drum is lowered by a 25 reversal of the direction of rotation of the gear R and its associated parts, until the drum rests once more upon the rollers D and D'.

In the modified form shown in Figure 3, 30 there is substituted for the upwardly acting jack P, the tackle V suspended from the pulley W, and actuated for raising and lowering by means of the motor X or equivalent hoisting means, the pulley W being supported from the over-engaging frame Y. 35 This latter may be also made to serve as the support for a track Z, along which a car Z' of material may be run until it is in position for dumping into the upturned filling opening B in the drum A. The same principle 40 applies as to the bar J being the rotative center, about which the body of the drum is lifted, as is the case when the jack shown in Figure 1 is relied upon.

What we claim is:

45 1. In combination with a rotatable furnace drum, means on one side thereof adapted to cooperate with a removable external supporting member in constituting a laterally disposed turning axis, and means for lifting upon the opposite side of the drum, 50 whereby the elevation thereof is through an arc whose center is located coaxially with said turning axis.

55 2. The combination, with a rockable furnace drum, of means adapted to be detachably correlated with one side of said drum adjacent the line of the pouring orifice whereby the drum is temporarily supported against further rotative movement, and elevating 60 means adapted to act upon the opposite side of the drum from said detach-

able supporting means, whereby the drum is caused to travel through an arc whose axial center is coincident with the line of contact between the drum and its temporary support. 65

3. The combination of a rotatable furnace drum normally resting upon peripherally engaging rotatable supports, an external support adapted to be placed in engagement 70 with one side of the drum adjacent the line of its pouring orifice, and means for elevating the opposite side of the drum about its line of contact with said external support as a center, thereby placing the pouring orifice 75 in a more favorable pouring position.

4. In combination with a rotatable furnace drum, removable means for supporting that side thereof wherein the pouring orifice is located when in pouring position, means for elevating the drum about the line of support 80 as a turning center, and means for successively presenting a plurality of molds for filling from the pouring spout as thus located. 85

5. In combination with a rockable furnace drum, means for temporarily supporting that portion of the drum wherein the pouring spout is located when in pouring position, and means for elevating the opposite side of the drum about the line of contact with said temporary supporting means as a center. 90

6. The combination, with a rockable furnace drum, of means for temporarily supporting against further rotative movement a selected peripheral point adjacent the pouring spout of the drum, and means adapted to act upon a peripherally distant portion of the drum, to raise the same about said holding point as a center. 95

7. In a rotatable metal-treating furnace, in combination with a rotatable drum, removable supporting means adapted to be placed in operative relation to said drum adjacent the pouring orifice therein, and means adapted to act upon a peripherally remote portion of the drum from that engaged by said supporting members, whereby the same 100 may be elevated to pouring position through an arc whose axial center is coincident with the line of contact of said drum and said removable supporting members. 110

In testimony whereof, we, OLIVER J. MARSHICK and EDWIN L. CROSBY sign this specification in the presence of two witnesses. 115
